CHILD'S RAIN BOOT OR THE LIKE ARTICLE

Martin Kaye, New York, N. Y., assignor to The Goodyear Rubber Company, Middletown, Conn., a corporation of Connecticut

Application February 25, 1950, Serial No. 8,115

Term of patent 14 years

(Cl. D7—4)

To all whom it may concern:

Be it known that I, Martin Kaye, a citizen of the United States of America, residing at Borough of Manhattan, in the city, county, and State of New York, have invented a new, original, and ornamental Design for a Child's Rain Boot or the Like Article, of which the following is a specification, reference being had to the accompanying drawing, forming part thereof.

In the drawing:

Fig. 1 is a front perspective view of a child's rain boot, the opposite side presenting substantially the appearance of the side shown, showing my new design; and

Fig. 2 is a rear perspective view of said boot.

I claim:

The ornamental design for a child's rain boot or the like article, substantially as shown and described.

MARTIN KAYE.
